(57) **CLAIM**

The ornamental design for computer mouse, as shown and described.

DESCRIPTION

FIG. 1 is a perspective view of a computer mouse showing our new design;

FIG. 2 is a second prospective view thereof;

FIG. 3 is a top plan view thereof;

FIG. 4 is a bottom plan view thereof;

FIG. 5 is a front elevational view thereof;

FIG. 6 is a rear elevational view thereof;

FIG. 7 is a left side elevational view thereof; and,

FIG. 8 is a right side elevational view thereof.

The broken lines shown to be immediately adjacent to the shaded/contoured areas represent certain portions of the bounds of the claimed design while all other broken lines are directed to environment and are for illustrative purposes only; the broken lines from no part of the claimed design.
